UNITED STATES PATENT OFFICE.

FRANK G. O'ROURKE, OF LACKAWANNA, NEW YORK.

ROTARY ENGINE.

Application filed September 18, 1921. Serial No. 500,347.

To all whom it may concern:

Be it known that I, FRANK G. O'ROURKE, a citizen of the United States, and a resident of Lackawanna, in the county of Erie 5 and State of New York, have invented certain new and useful Improvements in Rotary Engines, of which the following is a specification.

This invention relates to rotary engines 10 and is an improvement over the construction illustrated in my United States Patent No. 1,247,868.

An important object is to provide a rotary engine of the type embodied in my patent 15 which is provided with novel means whereby the abutments are advanced and retracted at the proper period.

Further, the invention aims to provide novel means whereby the supply of fluid under pressure to the expansion chambers or 20 cylinders is automatically controlled.

A further object of the invention is to provide a rotary engine which is of highly simplified construction, durable in use and 25 comparatively cheap to manufacture.

Other objects and advantages of the invention will be apparent during the course of the following description.

In the accompanying drawings forming 30 a part of this application and in which like numerals are employed to indicate like parts throughout the same,

Figure 1 is a side elevation of the improved engine,

Figure 2 is a vertical transverse sectional view through the same, the view being taken on line 2--2 of Figure 1,

Figure 3 is a fragmentary perspective illustrating the means for controlling the fluid 40 pressure valve,

Figure 4 is a vertical sectional view illustrating the stator and the piston arranged therein,

Figure 5 is a fragmentary perspective 45 view illustrating the piston and the shaft supporting the same, and

Figure 6 is a detail sectional view through the abutment casing, the view illustrating the abutment.

In the drawing, wherein for the purpose 50 of illustration is shown a preferred embodiment of the invention, the numeral 10 designates spaced members upon which stators generally designated by the numeral 11 are mounted, the said stators being composed 55 principally of oppositely arranged heads

having inwardly directed flanges 13 through which bolts or other fastening devices 12 are extended for the purpose of connecting the several sections of the stators. 60

Each stator is provided with oppositely directed bearings 14 having packing means 15 secured in place by means of adjusting devices 16. The shaft 17 which extends through the several stators is extended 65 through a bearing 18 mounted on the upper portion of a pedestal 19 arranged between the stators.

As illustrated in Figures 4 and 5, a piston 20 is extended radially from the shaft 17 70 and is rotatable within the chamber of the stator and cooperates with a sliding abutment 22 in forming expansion chambers adapted for the reception of fluid under 75 pressure.

The abutment 22 is slidable within a casting 24 secured to the stator beneath one of the bearings 14 and having a detachable cover 25. The sliding abutment 22 which is adapted to extend across the interior of the 80 stator, is provided with a rod 26 connected to a link 27 as indicated at 28 and having one end joined with the downwardly extending branch of a bell crank generally designated by the numeral 29. The upper 85 branch of the bell crank 29 is provided with a head or roller 30 arranged in the path of travel of a cam 31 secured on the shaft 17 by means of a set screw 32 or other suitable means. It will be observed that when the 90 shaft 17 is rotated, the cam 31 will also be rotated for depressing the upper portion of the bell crank 29. Therefore, when the lobe of the cam 31 engages the head 30, the link 27 and consequently the abutment 22 will 95 be moved longitudinally for permitting the passage of the piston 20.

However, when the lobe of the cam 31 is out of contact with the roller, the abutment 22 is moved to its advanced position by the 100 fluid pressure from a fluid pressure conveying pipe 35 extended into the abutment casting 24. It is thus seen that when the lobe of the cam 31 is out of engagement with the bell crank 29, the abutment is urged to its 105 advance position by the pressure of the fluid conveyed to the pipe 35.

Fluid under pressure is conducted to the stator by means of a valve contained within a casing 40 and having a valve stem 41 provided with a laterally directed crank 42. The laterally directed crank or arm 42 of the 110

valve stem 41 has connection with the longitudinally movable link 44 connected to the forked upper end 46 of a swinging operating arm generally designated by the numeral 5 47. As illustrated in Figure 3, the swinging operating member 47 includes two lengths of metal pivoted to a base 48 as indicated at 49. The upper portions of the 10 lengths of metal from which the operating member 47 are formed, are curved outwardly to form the arms 46 and the lengths of metal are connected immediately below the curved portions 46 by a spacing block 50. The spacing block 50 is provided with 15 an upwardly directed pin 51 slidable within the cam groove 52 in a cam 53, keyed or otherwise secured to the shaft 17. As the shaft 17 is rotated, the curved portions 46 of the operating member 47 will be operated, 20 since the upwardly directed pin 51 is received within the cam groove 52. Therefore, the operation of the member 47 will reciprocate the link 44 for periodically operating the valve connected to the stem 40. 25 Fluid under pressure is supplied to the two casings 40 by means of pipes 60 extending from a main pipe 61 and discharging into the side of the casing 40. As illustrated in Figure 4, the fluid under pressure enters 30 the two stators 18 by means of ports 64 formed in the inner wall of the stators. An exhaust pipe 65 receives the exhaust from the port 64.

Each stator is also provided with an exhaust casing 70 having a valve similar in 35 construction to the valve casing 40 and provided with a stem 71 to which a crank 72 is connected, the said crank being pivoted to an operating link 73 connected to one of the 40 longitudinally curved arms 36 of the adjacent valve operating member 47. It will be seen that the rocking movement of the valve operating member 47 will not only operate the intake valves, of which there are two, 45 but also the exhaust valves which are arranged on opposite sides of the abutment casings 24.

In operation, the fluid under pressure is supplied at the proper intervals to the chambers of the several stators by means of the 50 valves and the fluid contacts with the beveled edges 66 of the pistons 20 and thereby forces the pistons to rotate for imparting a similar motion to the shaft 17. When the piston 20 approaches the abutment 22, the abutment is moved outwardly so as to permit of the passage of the piston. When the piston passes the abutment 22, the intake valves are again opened and the abutments are returned to their advance positions by 55 means of the fluid under pressure supplied from the pipes 35.

I claim:

1. A rotary engine comprising a stator, a shaft extending through the stator and provided with a radial piston, a valve casing having a valve for controlling the supply of fluid under pressure to said stator, said valve being provided with a laterally directed arm, a link connected to said arm, a link operating member inclusive of a base, an arm pivoted thereto and having its upper portion forked to provide a pair of arms pivotally connected to said link, a pin connected to said forked portion of the arm, a cam having a cam groove receiving said pin, whereby to reciprocate said link periodically, and means to supply said casing with fluid under pressure. 75

2. A rotary engine comprising a stator, a shaft extending through the stator and provided with a radial piston, a valve casing having a valve arranged therein and provided with a stem, a link cooperating with said stem, a link operating member inclusive of a base and upstanding arms pivoted thereto and having their upper portions forked, the intermediate portions of said arms being provided with a spacing block, a pin carried by said spacing block, and a cam having a cam slot receiving said pin, one of the forks of said arms having its terminal pivoted to said link. 80 85 90

FRANK G. O'ROURKE.
